UNITED STATES PATENT OFFICE

ALFRED CROSSLEY, OF WASHINGTON, DISTRICT OF COLUMBIA, ASSIGNOR, BY MESNE ASSIGNMENTS, TO FEDERAL TELEGRAPH COMPANY, A CORPORATION OF CALIFORNIA

THERMOSTATIC CONTROL SYSTEM

Application filed May 27, 1927. Serial No. 194,797.

My invention relates broadly to electrical control circuits and more particularly to a thermostatic control circuit capable of controlling the operation of an electrical circuit over a limited and predetermined temperature range.

One of the objects of my invention is to provide an electron tube thermostatic control circuit having means for effecting the opening or closing of an electrical circuit in accordance with a predetermined temperature condition.

Another object of my invention is to provide a thermostatic electron tube control circuit that is responsive to slight changes in temperature for closing or opening an electrical circuit.

My invention finds particular application in piezo electric crystal control circuits where it is necessary to maintain the piezo electric element at a constant frequency. The circuit arrangement of my invention is capable of holding the temperature of a crystal container to within less than one-tenth of a degree centigrade of a specified temperature.

My invention will be more fully understood from the specification hereinafter following by reference to the accompanying drawings in which:

Figure 1 is a side elevation of one construction of a thermostatic control device employed in the circuit of my invention; Fig. 2 shows diagrammatically the arrangement of the thermostatic control circuit of my invention; and Fig. 3 shows the application of the control circuit of my invention to a piezo electric crystal controlled transmitter circuit.

In obtaining the fine temperature adjustment of the apparatus of my invention, I provide a mercury column or a bi-metallic expansion member either of which has a multiplying feature. The mercury column or capillary tubing should be of as small a bore as possible and the mercury base bulb

should be relatively large in order that a small change in temperature will cause a large change in height of the mercury column. The bi-metal expansion member may consist of a spiral strip and a long arm with 50 suitable contact members thereon for cooperation with a fixed contact. When such a device is directly connected in a control circuit the contact will permit the interrupting of but a minute quantity of current without 55 damaging the contacts either from arcing at the metal contact, or from oxidizing the surface of the mercury, which in turn ruins the adjustment for fine control of temperature. I have experienced this difficulty in 60 connection with the control of piezo electric crystal oscillators and have devised the circuit disclosed herein that permits the use of a negligible current flow through the mercury or bi-metallic thermal system to provide a 65 method of accurate temperature control.

In Fig. 1, I have shown a bi-metallic contact member 1 having parts 1a and 1b of different coefficients of expansion. The bi-metallic member 1 carries a contact 2 at one end 70 thereof that is arranged to close or open an electrical circuit to the adjustable contact member 3 carried by the screw threaded member 4 in the standard 5. I may also employ a mercury expansion member as shown at 12 75 in Fig. 2 that consists of a glass container with a well of mercury 15 at its base and a capillary tube associated with the well that causes the rise and fall of a fine column of mercury with changes in temperature. A 80 tungsten or iron wire 33 is placed in the well and passes through a glass seal to the exterior of the bulb, and thence to the battery 16. Another tungsten wire 14 is inserted in the capillary tube to provide the make and break contact with the mercury column when under influence of temperature changes. A source 85 of grid biasing voltage is shown at 9 and 16. Connected to the negative end of the battery 9 is a high resistance 8 of a value from 100,000 90

- to 500,000 ohms, the opposite terminal of which is connected direct to the grid 6b of the vacuum tube 6. The tube has the customary filament 6a, heating battery 7, plate circuit 27 that is coupled to the inductance 30 in antenna-ground circuit 31. The temperature control equipment is similar to that shown in Fig. 2.
- It is therefore apparent that changes in temperature at the piezo electric crystal element 22 will affect the thermostatic control system and turn on or off the heater coil 19. The application of my invention to piezo electric crystal controlled transmitters is of extreme importance as constancy of frequency control can only be maintained while the piezo electric crystal element remains at a uniform temperature. The control system of my invention is extremely accurate, is effected by minute changes in temperature conditions, and provides for the piezo electric crystal element being subjected to heat, or the heat may be cut off from the container, in accordance with variations in temperature immediately adjacent the piezo electric crystal element.
- It will be observed that the heater circuit is normally closed and will remain so while the temperature is below a predetermined limit. However, when the temperature rises beyond the limit, the heater coil is cut off to be connected again when the temperature has dropped below the selected limit. Suitable means may be provided for selectively adjusting the predetermined limit.
- While I have described my invention in certain of its preferred embodiments, I desire that it be understood that modifications may be made and that no limitations are intended other than are imposed by the scope of the appended claims.
- What I claim as new and desire to secure by Letters Patent of the United States is as follows:
1. An electrical control circuit comprising an electron tube having grid, filament and plate electrodes, an input circuit included between said grid and filament electrodes, an output circuit included between said plate and filament electrodes, a relay disposed in said output circuit, separate potential sources having a common connection to said filament, a temperature controlled switch in said input circuit, means for normally subjecting said grid electrode to a predetermined bias potential, said temperature controlled switch being operative to connect said grid electrode to the other of said sources for abruptly changing the effective bias potential on said grid electrode under conditions of temperature variation for correspondingly controlling said relay.
  2. An electrical control system comprising an electron tube having grid, filament and plate electrodes, an input circuit including said grid and filament electrodes, an output circuit including said plate and filament electrodes, a relay disposed in said output circuit, a temperature controlled switching device, independent sources of potential connected

with said device and having a common connection with said filament, means for normally impressing a negative potential upon said grid electrode from one of said sources of potential, said switching device being responsive to changes in temperature for abruptly impressing a positive potential on said grid electrode from the other of said sources of potential for controlling the operation of said relay.

3. An electrically controlled circuit comprising an electron tube having grid, filament and plate electrodes, an output circuit connected between said plate and filament electrodes, a relay included in said output circuit, an input circuit connected between said grid and filament electrodes, to independent sources of potential having a common connection with said filament, a temperature controlled switch in said input circuit, means for normally impressing a negative potential on said grid electrode from one of said sources for rendering said relay in said output circuit inactive, and a circuit in shunt with said input circuit including the other of said sources of potential, a positive charge upon said grid electrode upon changes in temperature conditions for activating said relay under control of said temperature controlled switch.

4. An electrical control system comprising an electron tube having grid, filament and plate electrodes, an input circuit including said grid and filament electrodes, an output circuit including said plate and filament electrodes, a relay disposed in said output circuit, said input circuit including a source of potential connected to normally impress a negative charge on said grid electrode for rendering said relay in said output circuit inoperative, an auxiliary circuit in shunt with said input circuit, said auxiliary circuit including an independent source of potential and a temperature controlled circuit maker and breaker operative upon increases in temperature to close a circuit from said grid electrode to said independent source of potential for abruptly impressing a positive charge on said grid electrode from said independent source of potential for activating said relay in accordance with temperature changes.

5. A piezo electric crystal controlled transmission system comprising an oscillator, a piezo electric crystal member for controlling the operation of said oscillator, a temperature controlled circuit maker and breaker positioned adjacent said piezo electric crystal member and subject to the same conditions of temperature to which said piezo electric crystal is subjected, a heater coil adjacent said piezo electric crystal member, and an electron tube circuit disposed between said temperature controlled circuit maker and breaker and said heater coil, a grid circuit, a plate circuit, a relay in said plate circuit for controlling said

heater coil, and means controlled by said circuit maker and breaker for subjecting said grid circuit to abrupt polarity changes for actuating the relay in said plate circuit for regulating the heating effect of said heater coil in accordance with changes in temperature and maintaining said piezo electric crystal member under conditions of uniform temperature for the generation of constant frequency oscillations.
